2,566,041

STEAM HEATING BOILER CONTROL SYSTEM

Lawrence C. Simmons, Ossining, N. Y., assignor
to The New York Central Railroad Company,
New York, N. Y., a corporation of New York

Application September 26, 1947, Serial No. 776,304

27 Claims. (Cl. 158—36)

1

This invention relates to steam heating boiler control systems, and particularly to means for controlling and regulating the supplies of fuel, such as liquid hydrocarbon fuel, and a gaseous fuel atomizing or conditioning medium, such as air or steam, or both, to the burner of a boiler heater or steam generator of a steam heating or supply system. More particularly the invention relates to a steam generator and controlling and regulating means of the character described for installation on an electric or Diesel locomotive or on a baggage or other car for cooperation with steam heating apparatus of standard cars or coaches to supply steam for heating the same. The invention is especially adapted for use on electric locomotives for supplying steam to the cars of a train being hauled by an electric or Diesel locomotive substituted for a steam locomotive. The invention is, however, capable of use on other vehicles or in stationary plants where the steam is utilized for either heating or power purposes.

The present invention is designed as an improvement upon the control system covered by Hamilton and Rowell, Patent No. 2,116,943, dated May 10, 1938, particularly with relation to means for controlling and regulating the supplies of the fuel and a fuel conditioning element or whirling agent to the burner whereby the boiler or steam generator is heated, so that a wide-range low-pressure burner of whirl-type producing and burning a highly atomized fuel, may be used, with resultant greater economy and efficiency as compared with those heretofore used.

One object of the invention is to provide a control means of the character and for the purpose described which is simple of construction but adapted to control the supplies of the fuel and conditioning and whirling agent to the burner in a regulated manner as required and automatically responsive to boiler conditions.

Another object of the invention is to provide a control system which reduces liability of irregularities in the burner operation and effects a saving in the use of the fuel and its conditioning agent.

With these and other objects in view, the invention consists of the features of construction, combination and arrangement of parts, herein-after fully described and claimed, reference being had to the accompanying drawings, in which:

Figure 1 is a diagrammatic view of a heating system embodying the novel features of my invention.

Figures 2 and 3 are similar views of the wiring of the electric control circuits thereof.

2

Figure 4 is a longitudinal section of the burner employed in the system.

Figure 5 is a longitudinal section through parts shown in Figure 4 on an enlarged scale.

Figures 6, 7, 8 and 9 are cross-sections on the lines 6—6, 7—7, 8—8 and 9—9 of Figure 5.

Figure 10 is a cross-section on line 10—10 of Figure 11 through the burner tip.

Figure 11 is a view partly in side elevation and partly in section, taken on line 10—10 of Figure 9 of the burner tip.

Figure 12 is a perspective view of the feed plug.

This new control system is designed for use with a low-pressure, wide-range type of burner such as shown, for example, in Figures 4 to 12 herein and covered by my application for patent filed September 26, 1947, Ser. No. 776,303, and executed of even date herewith, or with other burners of the same type. The control system, 15 which varies in certain important particulars from that shown in the Hamilton and Rowell patent to control the supply of atomizable fuel with air or air and steam as a gaseous combustion-promoting and whirling medium to the burner for a starting action and to thereafter 20 preferably supply steam alone as the combustion-promoting and whirling medium and to regulate the supply of fuel and steam to the burner according to working conditions in the boiler, so as to ensure proper atomization of the fuel and economy, efficiency and safe operation of the apparatus under all conditions, as hereinafter described.

Referring now more particularly to Figure 1 of the drawings, 1, 2 and 3 represent generally and respectively the main water, steam and air piping of the feed and control parts of the system; 4 the superheated steam service pipe for supplying steam to the car heaters; 5 the boiler or steam generator and 5^a its safety valve or valves; 6, 7, respectively, the hydrocarbon liquid and feed water supply tanks of the system; 8 the burner in the combustion chamber of the boiler; 9 the main fuel oil supply pipe, for conducting oil from the tank 7 to be pumped to the burner; 10 a steam driven water feed pump for supplying water from the tank 7 to the boiler; and 11 a turbo-electro-motor oil pump and blower unit for supplying the liquid fuel and combustion air to the burner, said unit comprising an electric motor 12, a steam turbine 13, an oil pump 14, and a blower 15, all of which, as well as certain water control features, not herein described, may conform generally to the similar parts shown in the aforesaid Hamilton and Rowell patent.

The burner 8 employed is one of wide-range

type having a whirl chamber for atomizing the fuel and tangential passages for supplying streams of atomizing air or steam thereto and causing the same to whirl in the chamber and eject from the chamber fuel oil in the form of minute globules.

This burner 8 comprises an outer jacket or casing 16 extending at its inner end into the combustion chamber of the boiler and provided at such end with a flame spreader 17. At its outer end the jacket is provided with a fuel inlet port 18, connected with the delivery end 9' of the fuel supply pipe 9, and with an air or steam inlet port 19 connected with an atomizing pipe 20. This pipe 20 in turn is connected with the pipe 3, which leads from a source of compressed air, such as the main air reservoir of the locomotive, and with a steam supply pipe 21 leading from the pipe 4, whereby compressed air or superheated steam may be supplied to the atomizing line for passage to the burner, as hereinafter described.

Disposed within the outer casing or jacket 16 is an inner burner casing or tube 22 having a cap 23 formed with an inwardly extending flange 24 defining an outlet opening 25 at the discharge end of the burner. In the casing or tube 22 is mounted a fuel conducting pipe or tube 26, the bore 27 of which forms an oil supply passage. This tube is spaced from the tube 22 and its cap 23 to provide an annular air or steam supply passage 28. Passage 27 communicates at its rear end with port 18, while passage 28 communicates at its rear end with port 19.

The bore or passage 27 of the conductor 26 is counterbored or recessed at its forward end, as at 29, to receive a hollow oil feed plug 30. This plug has an open rear end communicating with the passage 27 and is closed at its front end 31, the latter having a plane front face 31 lying flush with the forward end of the tube 26. The forward portion of this plug is externally reduced in diameter, as shown at 32, to form with the opposed portion of the wall of the recess 29 a shallow, annular oil delivery passage 33 opening outwardly about the face 31 of the plug. Formed in the plug is an annular set or series of equally spaced radial feed ports 34 which communicate at their inner ends with the interior of the plug and at their outer ends with said oil delivery passage 33. Oil under pressure may thus flow from passage 27 into the plug and outward through the ports 34 to the passage 33 for supply in a regulated amount to the burner tip or atomizer 35.

The burner tip or atomizer 35 is disposed between the forward end of the conductor 26 and the inwardly extending flange 24 at the front of the cap 23. This tip is of generally circular form and has a body portion 36 of less diameter than the internal diameter of the cap 23 but of greater diameter than the portion 32 of the plug 30, a front face 37, a rear face 38, and a central passage 39 forming a whirl chamber. The front face 37 of the tip is arranged to bear against the flange 24 of the cap 23 and adjacent thereto the tip is provided with a circumferential flange 40 which bears against the inner periphery of the cap and spaces the body portion 36 of the tip from said surface of the cap. The rear face 38 of the tip is arranged to bear against the front end of the conductor 26 and the front face 31 of the plug 30, and extending rearwardly from this face 38 of the tip is a flange 41 which overlaps the reduced front portion 42 of the conductor 26 and centers the tip with relation thereto and to the plug 30.

The burner tip is provided in its rear portion with a set of fuel and air or steam conducting channels or passages 43 and at a suitable point between said channels 43 and an ejection outlet 44 at the front of the whirl chamber 39 with a set of air or steam conducting channels or passages 45, the channels of each set extending from its periphery toward and entering the whirl chamber substantially tangentially thereto. The channels of each set are formed by boring or drilling them in contradistinction to milling them, by which they may be more economically produced and also more accurately dimensioned for fuel and steam supplies in proper ratios and arranged to secure a more efficient whirling action and atomization of the oil. At least two sets of channels are provided for these purposes, one for mixed jets of oil and air or steam and the other for jets of air or steam alone, to make up for reduction in the sizes of the channels necessitated by drilling and which in the use of a single set might cause undesirable restriction to steam flow. Any number of sets or rows of bored channels, suitably dimensioned and placed at spaced points axially of the tip, may be used to increase the whirl velocity and adapt the burner to atomize heavy hydrocarbon oils or to spin powdered coal at the velocity necessary to use it as fuel. In the present instance two such sets or rows of channels are disclosed to secure feed and velocity ratios sufficient for the fine atomization of hydrocarbon oil of a certain viscosity, but by the use of one or more additional rows velocities sufficient for atomization of heavier hydrocarbon oils or to spin powdered coal may be obtained.

In the construction illustrated the channels 43 are arranged at the inner end of the tip and consist of circular bores formed in the flange 41 and alined grooves in the face 38 extending from the flange to the inner end of the chamber 39, while the channels 45 are in the form of continuous circular bores extending from the outer periphery of the tip to and intersecting the chamber 39 at a point between the channels and the ejection outlet 44. As shown in this particular instance the channels 45 intersect the chamber 39 at a point somewhat in advance of its transverse center and between its transverse center and the outlet 44, but this arrangement may be varied as circumstances may require. The grooved portions of the channels 43 are closed at the rear by the surface 31 of the plug 30 and communicate with the oil feed passage 27 at a point between their outer ends and the chamber 39, while both sets of channels 43 and 45 communicate at their outer ends with the air or steam passage 28. While steam has been more particularly described above as the atomizing, combustion-promoting and whirling medium, used, it is to be understood that under certain conditions or for certain installations air, air and steam combined, or any suitable gaseous whirling medium may be employed.

In the operation of the burner for general purposes, the liquid fuel to be atomized is supplied continuously to the passage 27, from which it flows into the plug 30 and through the ports 34 in the latter to the annular passage 33, from which it is delivered into the channels 43 at an intermediate point in the length of each of said channels. At the same time low-pressure steam or air flows from the passage 28 into both sets of channels 43 and 45. The streams or jets of steam or air entering the channels 43 pick up and are intermixed with the fuel entering such channels 75 and these comingled streams enter the whirl

chamber 39 at high velocity and are caused to whirl therein by which a high degree of atomization of the fuel is effected. This whirling mass moves axially in the tip toward the ejection outlet 44 and meets the streams or jets of steam or air entering the tip through the channels 45. As these streams or jets entering through the channels 45 strike the whirling mass after it has already obtained a high velocity due to injection through the channels 43, the mass is whirled at a still higher velocity whereby the atomization of the fuel is increased to a much higher degree than is possible to obtain with burners of the ordinary type using milled slots or other forms or arrangements of channels. This is due to the fact that the efficiency of a jet is a function of the speed of a mass it is required to move. By the provision of the air or steam injection channels 45, the whirling speed is not only greatly increased, producing a higher degree of atomization, but the whirling agent, air or steam, is more intimately admixed with the minute oil globules, so that a fuel mixture of maximum combustibility is produced. This mixture feeds in the form of a slightly converging conical mass to the conical outlet 44 and then discharges in the form of a diverging hollow conical stream through the burner outlet 25, where it is suitably ignited.

The result of atomizing the fuel in the manner described is to provide a method of atomization which effects a saving in steam or air consumption and reduces liability of irregularities of action of the burner and furnishes a highly combustible fuel which will leave less residue, so that frequent cleaning of the burner is unnecessary. By increasing the number of rows of air or steam jets employed, the whirl velocity of the mass in the whirl chamber may be increased to degrees allowing atomization and burning of heavy liquid hydrocarbon fuels as well as the spinning and mixing of powdered coal with a whirling and combustion-promoting agent, so that low grade liquid hydrocarbon oils and powdered coal may be used as fuel with this type of burner.

In the operation of the burner as used in this system the operation air is preferably employed as the gaseous combustion promoting agent and whirling medium for supply to both sets of channels 43 and 45 in starting the burner into action and until steam generation begins from which time, as the steam line 21 is directly connected with the atomizing line leading to the burner, mixed steam and air will be supplied to the channels 43 and 45 until a certain boiler pressure is reached, after which the supply of air is cut off and steam alone supplied to both sets of channels 43 and 45 for use as the combustion promoting and whirling medium to secure greater burner efficiency in employing the burner in connection with a steam generator, as herein-after described. By thus mixing steam with the air as soon as possible after the burner is started, the temperature of the mixture is raised to secure quicker high atomization of the fuel while air is being used, without liability of leakage of steam into the air line before the air supply is cut off.

It is to be understood that the delivery ends of the sets of passages 43 and 45 may communicate with the whirl chamber in longitudinal alignment with each other, or that they may be staggered relative to each other or otherwise arranged to secure a proper whirling action in the whirl chamber.

The blower employed is of the paddle type and

the fuel pump is of the gear type. The fuel pump shaft is directly connected to a shaft carrying the blower rotor, the steam turbine rotor and the electric motor armature. In normal operation, the shaft is driven by the turbine, the speed being controlled by automatically throttling the steam supply to the turbine according to the rate of combustion required to maintain boiler pressure. In order to drive the blower set when steam is not available, as in starting a cold boiler, the electric motor is used. This motor has not sufficient power to drive the set at full speed, and steam is, therefore admitted to the turbine as soon as the boiler starts to generate steam. The electric motor is also not depended upon for blower drive, as it is necessary to keep up steam even when power is shut off from the third rail or other source of electric current supply. The combustion control is based upon the fact that air delivered by a blower and fuel oil delivered by a rotary pump both vary directly as the speeds of the shafts. When the fuel pump is driven by the blower shaft there is obtained a fixed ratio between volumes of air and fuel delivered in a unit time, as they are both varied coordinately and concomitantly by changing the speed of their common drive shaft.

The steam supply connections include, in addition to the pipe line 2, the pipe line 4, leading from a super-heater 46, and the pipe line 21 leading from the line 4, a pipe 47 leading from the pipe 4, a pipe 48 leading from the pipe 2, and a pipe 49 leading from the pipe 48 to the steam turbine 13. In pipe 21 is an atomizing steam control key-metering valve 50; in pipe 48 is a blower motor control pressure switch 51 controlling a blower motor contactor 58 governing the flow of current from the current source to the blower motor 12 and also operating to close a valve 60 to stop the flow of air to the atomizing burner when the steam pressure is sufficient for atomizing the oil; and connected to pipes 47 and 48 is a diaphragm-operated turbine throttle valve 52 which is subjected to the opposing forces of a spring tending to open the valve 52 and boiler pressure on top of the diaphragm tending to close the valve. These forces are so proportioned that they throttle the steam to the turbine when the boiler pressure approaches maximum and increases the flow of steam to the turbine when the boiler pressure starts to fall away from maximum. When the boiler is in normal operation generating steam the speed of the blower-motor set is controlled through this valve 52 as a function of boiler pressure, the valve throttling the steam to the turbine and vice versa. A key-metering valve 52a is provided in a by-pass line around valve 52 to supply sufficient steam to drive the turbine blower motor fuel pump set at a low speed and maintain the fire when the boiler pressure has reached its maximum value and valve 52 is closed.

The flow of fuel oil from the pump is adjusted by opening or closing a by-pass valve 53. A pressure relief valve 54 in the fuel line is set to open at 200 lbs. pressure to protect the pump from high pressures. In the fuel line is also a relief valve 55 set to start opening at 20 lbs. through which nearly all the oil to the burner must pass. Its purpose is to maintain a minimum pressure on the pump discharge line of such value that the influence of back pressure from the fuel tank through valve 53 will have no appreciable effect on the flow of oil to the burner. This valve 55 has another desirable and important action. At

low speeds of the blower-motor-turbine oil pump the discharge of the oil pump is insufficient to keep the oil pressure up so that the relief valve throttles the flow of oil in the main fuel line to the burner. This throttle action works through the whole range of operation of valve 55 from closed to fully open position, or vice versa. Such action of the valve is ideally suited to the standby load on the boiler which occurs when the train line valve is closed, as it reduces the fuel supply to the burner more than the air from the blower is reduced. The percentage of CO₂ in the exhaust is thereby reduced and the boiler settled at a certain pressure below the safety valve settings without introducing any other control mechanism to obtain this very desirable low-fire condition. A valve 56 is provided to allow some oil to by-pass valve 55 when the pump discharge pressure is below 20 lbs. The feed of oil to the burner is controlled by an electric solenoid valve 57 capable of stopping all oil flow to the burner. It is interlocked with the atomizing pressure through blower motor contactor switch 58 in such manner that an atomizing pressure of 8 lbs. is necessary to close an atomizer pressure control switch 59 and complete an electric circuit to the valve 57. If the atomizing pressure drops below 5 lbs. switch 59 opens and de-energizes valve 57, stopping the flow of fuel oil to the burner.

It will thus be understood that relief valve 55 starts to close and thereby throttle the flow of fuel to the burner at the lower blower-motor-turbine fuel pump speeds or when valve 52 is closed or nearly closed. Thus the flow of fuel to the burner is reduced below the amount necessary for good combustion and a low or inefficient flame is produced in the fire-box. The effect of the inefficient flame allows the boiler to operate without blowing the safety valves during a stand-by period without letting the fire go out. By-pass valve 56 protects the system in the event that valve 55 closes completely by allowing enough fuel to flow to the burner to sustain a low flame.

In the atomizing line 20, with which pipes 3 and 21 connect and in which switch 59 is located, is also located an electric solenoid valve 60 which, when energized, allows air from pipe 3 to flow to the burner. It is interlocked to the contactor switch 58 so that when the electric drive to the blower-motor set is disconnected by the opening of switches 51 and 58 valve 60 is also closed to stop the flow of air to the burner. A key-metering valve 61 in the atomizing line regulates the flow of air to the burner. It is adjusted to reduce the steam pressure from 210 lbs. to 18 lbs. at the normal steam flow required for the burner. A relief valve 62 is provided in the atomizing line to prevent the accumulation of more than 25 lbs. pressure.

The main and blower-motor-turbine circuits are shown in Figures 2 and 3. The blower-motor circuit includes a source of current supply and the blower-motor contactor switch 58, while the main circuit includes a circuit breaker through which the circuit is energized with current from a battery or other supply source on the car, a starting switch 63, a stop switch 64, a starting and running relay 65, blower-motor control pressure switch and contactor 51, atomized pressure control switch 59, fuel line magnet valve 57, air magnet valve 60, and blower-motor contactor 58'.

In starting the boiler, on closing of switch 63, current passes through the turbo-blower-motor

5 pressure switch 51, thus energizing coil 58' and closing switch 58. This starts the blower-motor-turbine pump set, which forces air into the fire-box and oil to the fuel valve 57. Through an interlock on 58', or directly, current passes to air supply valve 60, opening the air line from the main reservoir to the burner through the atomizing line 20. When the pressure in the atomizing line builds up to 8 lbs. switch 59 closes and passes current to the valve 57 which opens and allows flow of oil to the burner. The oil is then atomized in the manner described and ignited by torch or spark ignition and the boiler starts absorbing the heat of combustion. When the boiler starts to make steam, the blower-motor-turbine-oil set speed is increased by the flow of steam to the turbine through line 49 and steam is also admitted to the atomizing line 20 from line 21. The valve 61 prevents the atomizing pressure from building up to more than 25 lbs. At 175 lbs. boiler pressure valve 51 opens, cutting out the electric drive from the blower-motor-oil pump set and shutting off the air supply from pipe 3 to the burner. The blower-motor-turbine-oil set is now driven by steam supplied to the turbine, which is controlled by the valve 52 as a function of boiler pressure. As the pressure increases or decreases valve 52 throttles the steam to the turbine, and vice versa. The functions of the other control parts in the generating action after generation begins have been described in the foregoing description.

From the foregoing description, taken in connection with the drawings, the construction, mode of operation and advantages of my improved fuel control means will be readily understood without a further and extended description. While the construction disclosed is preferred, it will, of course, be apparent that changes in the form, arrangement and details of construction of the parts may be made within the scope of the appended claims without departing from the spirit or sacrificing any of the advantages of the invention.

Having thus described my invention, I claim:

- 45 1. In a steam generator, a boiler, a burner for heating the boiler, fuel supplying means including a fuel supply line and a pump arranged therein for supplying fuel therethrough to the burner, an air supply line in connection with a source of supply of compressed air independent of the fuel supplying means for supplying air to the burner to atomize the fuel in a starting action, a steam supply line connecting the boiler with the burner for supplying steam to the burner when the boiler is generating, an electrically controlled air cut off valve in the air line, an electric circuit including the valve, boiler pressure controlled switching means in said circuit operative when the boiler begins to generate steam at a predetermined pressure to cause said valve to close and cut off the supply of air to the burner, and means in the steam supply line for regulating the flow of steam therethrough to the burner.
- 50 2. In a steam generator, a boiler, a burner for heating the boiler, fuel supplying means including a fuel supply line and a pump arranged therein for supplying fuel therethrough to the burner, an air supply line in connection with a source of supply of compressed air independent of the fuel supplying means for supplying air to the burner to atomize the fuel in a starting action, a steam supply line connecting the boiler with the burner for supplying steam to the burner when the boiler is generating, an electrically controlled air cut off valve in the air line, an electric circuit including the valve, boiler pressure controlled switching means in said circuit operative when the boiler begins to generate steam at a predetermined pressure to cause said valve to close and cut off the supply of air to the burner, and means in the steam supply line for regulating the flow of steam therethrough to the burner.
- 55 3. In a steam generator, a boiler, a burner for heating the boiler, fuel supplying means including a fuel supply line and a pump arranged therein for supplying fuel therethrough to the burner, an air supply line in connection with a source of supply of compressed air independent of the fuel supplying means for supplying air to the burner to atomize the fuel in a starting action, a steam supply line connecting the boiler with the burner for supplying steam to the burner when the boiler is generating, an electrically controlled air cut off
- 60 4. In a steam generator, a boiler, a burner for heating the boiler, fuel supplying means including a fuel supply line and a pump arranged therein for supplying fuel therethrough to the burner, an air supply line in connection with a source of supply of compressed air independent of the fuel supplying means for supplying air to the burner to atomize the fuel in a starting action, a steam supply line connecting the boiler with the burner for supplying steam to the burner when the boiler is generating, an electrically controlled air cut off
- 65 5. In a steam generator, a boiler, a burner for heating the boiler, fuel supplying means including a fuel supply line and a pump arranged therein for supplying fuel therethrough to the burner, an air supply line in connection with a source of supply of compressed air independent of the fuel supplying means for supplying air to the burner to atomize the fuel in a starting action, a steam supply line connecting the boiler with the burner for supplying steam to the burner when the boiler is generating, an electrically controlled air cut off
- 70 6. In a steam generator, a boiler, a burner for heating the boiler, fuel supplying means including a fuel supply line and a pump arranged therein for supplying fuel therethrough to the burner, an air supply line in connection with a source of supply of compressed air independent of the fuel supplying means for supplying air to the burner to atomize the fuel in a starting action, a steam supply line connecting the boiler with the burner for supplying steam to the burner when the boiler is generating, an electrically controlled air cut off

valve in the air line, an electric circuit including the valve, and boiler pressure controlled switching means in said circuit operative when the boiler begins to generate steam at a predetermined pressure to cause the air cut off valve to close.

3. In a steam generator, a boiler, a gaseous atomizing type burner for heating the boiler, a pump for supplying fuel to the burner, an air supply line for supplying air to the burner to atomize the fuel in a starting action, a steam supply line connecting the boiler with the burner for supplying steam to the burner when the boiler is generating steam, an electrically controlled air out off valve in the air line, an electrical circuit including the valve, boiler pressure controlled switching means in said circuit operative when the boiler begins to generate steam at a predetermined pressure to cause said valve to close and cut off the supply of air to the burner, and a key metering valve in the steam supply line for regulating the flow of steam therethrough to the burner.

4. In a steam generator, a boiler, an atomizing burner for heating the boiler, a fuel supply line leading thereto, a pump for supplying fuel through said line to the burner, means for driving the pump, an automatically closing throttle valve in the fuel line between the pump and burner responsive to fuel pressure delivered by the pump so as to move to a maximum open position at a predetermined high pump speed and being variably movable between the same and its closed position at lower pump speeds, a fuel cut off valve in the fuel line between the throttle valve and burner, an atomizing line connected to the burner for delivering a gaseous atomizing agent at a predetermined operating pressure thereto, and pressure controlled automatic means for closing said cut off valve when the pressure in the atomizing line falls to a predetermined degree below the operating pressure.

5. In a steam generator, a boiler, an atomizing burner for heating the boiler, a fuel line leading thereto, a pump for supplying fuel through said line to the burner, means for driving the pump, a by-pass connection in the fuel line about the pump, a by-pass valve in said connection adjustable to control the flow of fuel from the pump, a relief valve in said connection to protect the pump from high pressures, an automatically opening throttle valve in the fuel line between said by-pass connection and the burner responsive to fuel pressure delivered by the pump to move to a maximum open position at a predetermined high pump speed and being variably movable between the same and its closed position at lower pump speeds, an electrically controlled fuel cut off valve in the fuel line between the throttle valve and burner, an atomizing line leading to the burner, means connected with the atomizing line for conducting a gaseous atomizing agent under pressure thereto, an electric circuit, a switch in said circuit for closing the fuel cut off valve, and pressure controlled means for operating the switch to cause said cut off valve to close when the pressure in the atomizing line falls to a predetermined low degree.

6. In a steam generator, a boiler, an atomizing burner for heating the boiler, a fuel supply line leading thereto, a pump for supplying fuel through said line to the burner, means for driving the pump, an automatically closing throttle valve in the fuel line between the pump and burner responsive to fuel pressure delivered by the pump to move to a predetermined open posi-

tion at a high pump speed and variably movable between the same and its closed position at lower pump speeds, a by-pass valve in the fuel line about the throttle valve to allow flow of fuel past the valve when said valve is closed, an electric circuit, an electrically controlled fuel cut off valve in the fuel line between the throttle valve and burner, an atomizing line connected with the burner, means for supplying an atomizing agent under pressure to the atomizing line, and pressure controlled switching means in said circuit operative to cause said cut off valve to close when the pressure in the atomizing line falls to a predetermined low degree.

7. In a steam generator, a boiler, an atomizing burner for heating the boiler, an electric circuit, a pump for supplying fuel to the burner, an electric motor in said circuit for driving the pump for a starting action, a steam turbine for driving the pump when generation of steam begins, an atomizing line leading to the burner, a conductor in communication with the atomizing line for supplying air from a source of compressed air supply to the burner for atomizing the fuel, a conductor for supplying steam to the turbine to drive the same, a conductor for supplying steam to the atomizing line for passage to the burner to atomize the fuel, a switch governing the supply of electric current to the motor to drive the motor for a starting action during which the pump is operated by the motor to supply fuel to the burner and atomizing air and steam are being supplied to the burner through the atomizing line, a boiler pressure controlled switch for cutting off the supply of electric current to the motor when the boiler generates steam at a predetermined pressure, a boiler pressure controlled cut-off valve in the electric circuit for cutting off the supply of atomizing air to the burner when such predetermined pressure is reached, and a pressure controlled valve in the first-named steam conductor to control the supply of steam to the turbine and regulate its speed as a function of boiler pressure.

8. In a steam generator, a boiler, an atomizing burner for heating the boiler, a pump for supplying fuel to the burner, an electric circuit, an electric motor in said circuit for driving the pump for a starting action, a steam turbine for driving the pump when generation of steam begins, an atomizing line connected to the burner, a conductor in communication with the atomizing line for supplying air from a source of compressed air supply to the burner for atomizing the fuel, a conductor for supplying steam to the turbine to drive the same, a conductor connected to the atomizing line for supplying steam to the burner to atomize the fuel, a switch in the electric circuit for supplying electric current to drive the electric motor for a starting action during which the pump is operated by the electric motor to supply fuel to the burner by the pump while atomizing air is being supplied to the burner through the air conductor, a boiler pressure controlled switch for cutting off the supply of current to the motor when the boiler generates steam at a predetermined pressure, a boiler pressure controlled cut-off valve for cutting off the supply of atomizing air to the burner when such predetermined pressure is reached, a pressure controlled valve in the first-named steam conductor controlling the supply of steam to the turbine and operative to regulate its speed as a function of boiler pressure, a normally open fuel cut-off valve in the fuel supply line between the

pump and burner, means in said fuel supply line for maintaining a feed pressure in said line above a predetermined low pressure during varying speed operations of the pump, and a pressure operated device for closing said fuel cut-off valve when the pressure in the atomizing line drops below a predetermined pressure.

9. In a steam generator, a boiler, an atomizing burner for heating the boiler, a pump for supplying fuel to the burner, an electric motor for driving the pump for a starting action, a steam turbine for driving the pump when generation of steam begins, a conductor normally in communication with the burner for supplying air thereto from a source of compressed air supply for atomizing the fuel, a conductor for supplying steam to the turbine to drive the same, a conductor for supplying steam to the burner to atomize the fuel, means for supplying electric current to drive the electric motor for a starting action during which the pump is operated thereby to supply fuel to the burner while atomizing air is being supplied to the burner through the air conductor, a boiler pressure controlled switch for cutting off the supply of current to the motor when the boiler generates steam at a pressure sufficient to supply steam through the first-named steam conductor to drive the turbine and to supply steam through the second-named steam conductor to the burner to atomize the fuel, and a boiler pressure controlled cut-off valve for cutting off the supply of atomizing air to the burner when such boiler pressure is reached.

10. In a steam generator, a boiler, an atomizing burner for heating the boiler, means including a source of fuel supply and a pump for supplying fuel from said source to the burner, means independent of the fuel supplying means and including a conductor for supplying air to the burner for atomization of the fuel for a starting action, a conductor for supplying steam from the boiler to the burner for atomization of the fuel when the boiler is generating steam, an electric circuit, an electrically operated cut-off valve in the electric circuit controlling the flow of air to the burner through the air supply conductor, a pressure responsive switch device in said circuit operative when the boiler pressure reaches a certain degree to cause said valve to close and cut off the supply of air to the burner, and means in said steam conductor for regulating the amount of steam flowing therethrough to the burner.

11. In a steam generator, a boiler, an atomizing burner for heating the boiler, means including a source of fuel supply and a pump for supplying fuel from said source to the burner, an electric motor for driving the pump, a steam turbine for driving the pump, means independent of the fuel supplying means and including a conductor for supplying air to the burner for atomization of the fuel for a starting action, a conductor for supplying steam from the boiler to the turbine to drive the turbine when a predetermined boiler pressure is reached, a conductor for supplying steam from the boiler to the burner for atomization of the fuel, an electric circuit, an electrically operated cut-off valve in the air supply conductor, a cut out switch controlling the supply of electric current to the motor, a switch controlling said cut-off valve, a pressure responsive device in said circuit controlling the action of said switches to cut out the electric motor and cut off the supply of air

5

to the burner when the boiler reaches the predetermined degree for driving the turbine, and a pressure controlled valve in the first-named steam conductor for controlling the supply of steam to the turbine.

12. In a steam generator, a boiler, an atomizing burner for heating the boiler, a pump for supplying fuel to the burner, an electric circuit, a motor in said circuit for operating the pump for a starting action, a steam turbine for operating the pump when the boiler is generating steam, a conductor in connection with a source of compressed air supply independent of the pump and its said operating elements for supplying air to the burner to atomize the fuel, an electrically operated cut-off valve in the air supply conductor, an electrically operated valve for cutting off the supply of current to the motor, switches in the electric circuit for controlling the valves, a boiler pressure responsive device controlling said switches and operative when the boiler after a starting action begins to generate steam at a predetermined pressure to actuate said switches so as to cause the first-named valve to cut off the supply of atomizing air to the burner and to cause the second-named valve to cut off the supply of current to the motor, a conductor for supplying steam from the boiler to the burner to atomize the fuel when the boiler is generating, a steam supplying system for supplying steam from the boiler to the turbine to drive the same, and a governing valve in said system for regulating the flow of steam from the boiler to the turbine.

35

13. In a steam generator, a boiler, a burner for heating the boiler, a pump for supplying fuel to the burner, an electric circuit, a motor in said circuit for operating the pump for a starting action, a steam turbine for operating the pump when the boiler is generating steam, a conductor in connection with a source of compressed air supply independent of the pump and its said operating elements for supplying air to the burner to atomize the fuel, an electrically operated cut off valve in the air supply conductor, a switch in the circuit for closing said valve, a switch in the circuit for cutting off the supply of current to the motor, a boiler pressure responsive device controlling said switches and operative when the boiler after being started into operation begins to generate steam at a predetermined pressure to actuate the switches to close the air cut off valve and to cut out the motor, a conductor for supplying steam from the boiler to the turbine to drive the same, a conductor for supplying steam to the burner to atomize the fuel, a valve in the first named steam conductor responsive to the boiler pressure when such predetermined pressure is reached to regulate the supply of steam from the boiler to the turbine, and a key-metering valve for regulating the flow of steam through the second-named steam conductor.

55

14. In a steam generator, a boiler, a burner for heating the boiler, a fuel supply line leading thereto, a fuel supply pump in said line, a blower for supplying combustion air to the boiler firebox, said pump and blower being concurrently operative to supply fuel to the burner and combustion air to the firebox in fixed ratio, a by-pass in the fuel line about the pump, a pressure relief valve in said by-pass, an electric motor for concurrently driving the pump and blower in a starting action and until the boiler is generating steam, a steam turbine for concurrently driving

75

the pump and blower when the boiler is generating steam at and above a predetermined pressure, means for supplying electric current to drive the electric motor, boiler pressure controlled electrical means for cutting off the supply of current to the electric motor when the boiler pressure reaches the predetermined degree, a steam supply conductor between the boiler and turbine, a pressure controlled valve for regulating the supply of steam through said conductor to the turbine when the boiler pressure reaches the predetermined degree, and an automatically closing, pressure-opened throttle valve in the fuel line between the by-pass and burner adapted to open to a maximum degree at a predetermined high pump speed and to close more or less at lower pump speeds to throttle the flow of fuel from the pump to the burner.

15. In a steam generator, a boiler, a burner for heating the boiler, a fuel supply line leading thereto, a fuel supply pump in said line, a blower for supplying combustion air to the boiler firebox, said pump and blower being concurrently operative to supply fuel to the burner and combustion air to the firebox in fixed ratio, a by-pass in the fuel line about the pump, a relief valve in said by-pass, an electric motor for concurrently driving the pump and blower for a starting action and until the boiler generates steam, a steam turbine for concurrently driving the pump and blower when the boiler is generating steam, means for supplying electric current to drive the electric motor, pressure controlled electric means for cutting off the supply of current to the motor when the boiler pressure reaches a certain degree, an atomizing line connected with the burner, means for supplying an atomizing gas thereto to atomize the fuel, a steam supply conductor connecting the boiler with the turbine, a pressure controlled valve in said conductor for regulating the supply of steam to the turbine, an automatically closing, pressure-opened throttle valve in the fuel line between the by-pass and burner adapted to open to a maximum degree at a high pump speed and to close more or less at lower pump speeds to throttle the flow of fuel from the pump to the burner to reduce the volume of fuel supplied to the burner below the fixed ratio and with respect to that of the volume of air being supplied by the blower to the boiler firebox in a unit of time so as to maintain the burner in action at a low pump speed, a fuel cut off valve in the fuel line between the throttle valve and burner, and a pressure operated device in the atomizing line operative when the pressure therein falls to a predetermined degree to close said fuel cut off valve.

16. In a steam generator, a boiler, an atomizing burner for heating the boiler, an atomizing line connected with the burner, means including a fuel supply pipe and a pump for supplying fuel from a source of fuel supply to the burner, an electric motor for driving the pump, a steam turbine for driving the pump, means independent of the fuel supplying means and including a conductor connected with the atomizing line for supplying air to the burner for atomization of the fuel for a starting action, a conductor connected with the turbine for supplying steam thereto, a conductor connected with the atomizing line at a point between the burner and the point of connection of the air conductor with the atomizing line for supplying steam to the burner for atomization of the fuel when the boiler is generating steam, an electric circuit, a switch for letting on

and cutting off the supply of current to the electric motor, an electrically operated air cut off valve in the atomizing line between said air conductor and the second-named steam supply conductor, an electric fuel cut off valve in the fuel supply line, a pressure operated switch in the atomizing line for energizing said valve to hold it open when a predetermined working pressure in the fuel line exists and operative to deenergize and cause said valve to close when the pressure in the atomizing line falls to a certain degree, a key-metering valve in the atomizing line between said air and steam supply lines for regulating the flow of air to the burner, a relief valve in the atomizing line between the burner and the steam supply pipe for preventing the accumulation of more than a predetermined degree of pressure in the line, a pressure responsive switch device in the electric circuit operative when the boiler pressure reaches a certain degree to cause said air cut off valve to close and cut off the supply of atomizing air to the burner and to simultaneously operate the first-named switch to cut off the supply of electric current to the electric motor, and a pressure controlled valve in the first-named steam conductor for regulating the supply of steam to the turbine.

17. In a steam generator, a boiler, an atomizing burner for heating the boiler, an atomizing line connected with the burner, means including a source of fuel supply and a pump for supplying fuel from said source to the burner, an electric motor for driving the pump, a steam turbine for driving the pump, means independent of the fuel supplying means and including a conductor connected with the atomizing line for supplying air to the burner for atomization of the fuel for a starting action, a conductor connected with the turbine for supplying steam thereto, a conductor connected with the atomizing line at a point between the burner and the point of connection of the air conductor with the atomizing line for supplying steam to the burner for atomization of the fuel when the boiler is generating steam, an electric circuit, an electrically operated cut off valve in the atomizing line between said air and steam supply conductors, a key-metering valve in the atomizing line between said supply pipes for regulating the flow of air to the burner, a relief valve in the atomizing line between the burner and the steam supply pipe for preventing the accumulation of more than a predetermined degree of pressure in the line, pressure responsive switching means in the electric circuit operative when the boiler pressure reaches a certain degree to cause the cut off valve to close and cut off the supply of atomizing air to the burner and to simultaneously cut off the supply of electric current to the electric motor, and a pressure controlled valve in the steam conductor leading to the turbine for controlling the supply of steam thereto.

18. In a steam generator, a boiler, an atomizing burner for heating the boiler, an atomizing line connected with the burner, means including a source of fuel supply and a pump for supplying fuel from said source to the burner, means independent of the fuel supplying means and including a conductor connected with the atomizing line for supplying air to the burner for atomization of the fuel in a starting action, a conductor connected with the atomizing line at a point between the burner and the point of connection of the air conductor with the atomizing line for supplying steam from the boiler to the burner for atomiza-

tion of the fuel when the boiler is generating steam, an electric circuit, an electrically operated cut off valve in the atomizing line between said air and steam supply conductors, a key-metering valve in the atomizing line between said valves 5 and steam supply pipe for regulating the flow of air to the burner, a relief valve in the atomizing line between the burner and the steam supply pipe for preventing the accumulation of more than a predetermined degree of pressure in the atomizing line, a fuel cut off valve in the atomizing line, a pressure controlled device operative to close the fuel cut off valve when the pressure in said line falls below a certain degree, a pressure responsive switch device in the electric circuit 10 operative when the boiler pressure reaches a certain degree to cause said air cut off valve to close and stop the supply of atomizing air to the burner, and a key-metering valve in the steam conductor regulating the supply of steam to the 15 burner.

19. In a steam generator, a boiler, an atomizing burner for heating the boiler, an atomizing line connected with the burner, means including a source of fuel supply and a pump for supplying fuel from said source to the burner, means independent of the fuel supplying means and including a conductor connected with the atomizing line for supplying air to the burner for atomization of the fuel for a starting action, a conductor leading from the boiler to the atomizing line and connected to the atomizing line at a point between the burner and the point of connection of the air conductor with the atomizing line for supplying steam from the boiler to the burner for atomization of the fuel when the boiler is generating steam, an electric circuit, an electrically operated cut off valve in the atomizing line between said air and supply conductors, a key-metering valve in the atomizing line between said supply 25 pipes for regulating the flow of air to the burner, a relief valve in the atomizing line between the burner and steam supply pipe for preventing the accumulation of more than a predetermined degree of pressure in the line, and a pressure responsive switch device in said circuit operative when the boiler pressure reaches a certain degree to cause said air cut off valve to close and cut off the supply of air to the burner.

20. In a steam generator, a boiler, an atomizing burner for heating the boiler, an atomizing line connected with the burner, means including a fuel supply pipe and a pump for supplying fuel from a source of fuel supply through the said pipe to the burner, means independent of the fuel supplying means and including a conductor connected with the atomizing line for supplying air to the burner for atomization of the fuel for a starting action, a conductor connected with the atomizing line at a point between the burner and the point of connection of the air conductor with the atomizing line for supplying steam to the burner for atomization of the fuel when the boiler is generating steam, an electric circuit, an electrically operated cut off valve for cutting off the flow of air to the burner through the atomizing line, between a fuel cut off valve in the fuel supply pipe, a pressure operated switch in the atomizing line for energizing said valve to hold it open when a predetermined working pressure in the atomizing line exists and operative to deenergize and cause said valve to close when the pressure in the atomizing line falls to a certain degree, pressure responsive switch device in the electric circuit operative when the boiler pressure reaches a cer- 30

tain degree to cause said valve to close and cut off the supply of atomizing air to the burner, and means for regulating the supply of the steam to the burner through the steam conductor.

21. In a steam generator, a boiler, a gaseous atomizing type burner for heating the boiler, a motor driven pump for supplying fuel to the burner, means including a conductor for supplying air from a source of supply independent of the pump to the burner for atomization of the fuel for a starting action, a normally open cut off valve in said conductor, a separate conductor for supplying steam from the boiler to the burner for atomization of the fuel when the boiler is generating, said conductors being in communication with the boiler for the supply of steam with the air to the burner when the air cut off valve is open and for the supply of steam alone to the burner when the air cut off valve is closed, and means responsive to boiler pressure to close the air cut off valve to cut off the supply of air to the burner when the pressure reaches a certain degree.

22. In a steam generator, a boiler, a gaseous atomizing type burner for heating the boiler, a fuel supply line connected with the burner, a motor driven pump for supplying fuel through said line to the burner, an air supply line for supplying air to the burner from a source of supply independent of the pump to atomize the fuel, a steam supply pipe leading to the burner, means responsive to boiler pressure and operating after generation of steam begins and when a predetermined boiler pressure is reached to close the air cut off valve, whereby during a generating period before such pressure is reached both air and steam will be supplied to the burner to atomize the fuel and whereby upon the closing of the cut off valve steam alone will be supplied to the burner to atomize the fuel, and means for regulating the supply of steam to the burner through the steam supply pipe.

23. In a steam generator, a boiler, a gaseous atomizing type burner for heating the boiler, a motor driven pump for supplying fuel to the burner, means including a conductor for supplying air from a source of supply independent of the pump to the burner for atomization of the fuel for a starting action, a normally open cut off valve in said conductor, a separate conductor for supplying steam from the boiler to the burner for atomization of the fuel when the boiler is generating, means responsive to boiler pressure to close the valve to cut off the supply of air to the burner when the boiler pressure reaches a certain degree, and means for thereafter regulating the speed of the fuel pump as a function of boiler pressure.

24. In a steam generator, a boiler, a burner for heating the boiler, a pump for supplying fuel to the burner, an electric motor for operating the pump, a steam turbine for operating the pump, means including a conductor for supplying air from a source of supply independent of the pump to the burner for atomization of the fuel for a starting action when the pump is driven by the electric motor, a normally open cut-off valve in said conductor, a separate conductor for supplying steam to the burner for atomization of the fuel when the boiler is generating and the pump is driven by the turbine, a conductor for supplying steam to the turbine, means responsive to boiler pressure for stopping the electric motor and closing the valve in the air conductor to cut off the supply of air to the burner

when the boiler pressure reaches a certain degree, and means for thereafter controlling the supply of steam to the turbine through the last-named conductor and regulating its speed as a function of boiler pressure.

25. In a steam generator, a boiler, a burner for heating the boiler, a pump for supplying fuel to the burner, an electric motor for operating the pump, a steam turbine for operating the pump, a conductor connected with a source of air supply independent of the pump for supplying air to the burner for atomization of the fuel for a starting action when the pump is driven by the electric motor, an electrically operated air cut-off valve in said conductor, a conductor for supplying steam from the boiler to the turbine, a conductor for supplying steam from the boiler to the burner for atomization of the fuel when the boiler is generating and the pump is being driven by the turbine, electrically operated switches and associated means responsive to boiler pressure for controlling said switches to cut out the electric motor and close the air cut-off valve to cut off the supply of air to the burner when the boiler pressure reaches a degree at which steam is supplied through the first-named steam conductor to drive the turbine, and means operative when such boiler pressure is reached for thereafter controlling the supply of steam to the turbine and regulating its speed as a function of boiler pressure.

26. In a steam generator, a boiler, a gaseous atomizing fuel burner for heating the boiler, an atomizing line leading to the burner, a pump for supplying fuel to the burner, an electric motor for driving the pump, a steam turbine for driving the pump, a conductor for supplying air from a source of supply independent of the pump through the atomizing line to the burner for admixture with the fuel when the pump is driven by the electric motor, a conductor for supplying steam from the boiler through the atomizing line to the burner for admixture with the fuel when the pump is driven by the turbine, a conductor for supplying steam from the boiler to the turbine to drive the latter when the boiler pressure reaches a certain degree, a pump-pressure-controlled throttle valve for regulating the flow of fuel from the pump to the burner, means responsive to boiler pressure for stopping the electric motor and cutting off the supply of air to the burner when the boiler pressure reaches a degree at which steam is being

supplied to drive the turbine, and means for thereafter controlling the supply of steam to the turbine and regulating its speed as a function of boiler pressure.

5. 27. In a steam generator, a boiler, a gaseous atomizing type burner for heating the boiler, a fuel supply line connected with the burner, a steam turbine driven pump for supplying fuel through said line to the burner, an air supply line 10 for supplying air to the burner to atomize the fuel from a source of supply of air independent of the pump, a normally open cut-off valve in the air supply line, a steam supply line for supplying steam from the boiler to the burner to atomize the fuel, a steam supply line for supplying steam from the boiler to the turbine to drive the pump, means responsive to boiler pressure and acting after generation of steam begins and when a predetermined boiler pressure is reached to 15 close the air cut-off valve, whereby during a steam generating period before such pressure is reached both air and steam will be supplied to the burner to atomize the fuel and whereby upon the closing of the air cut-off valve steam alone 20 will be supplied to the burner to atomize the fuel, and boiler pressure controlled means operating when such predetermined boiler pressure is reached to control the supply of steam to the turbine to regulate the speed of the turbine and 25 30 pump as a function of boiler pressure.
